UNITED STATES PATENT OFFICE.

WILLIAM S. ROGERS, OF VAN BUREN, ARKANSAS.

HORSE COLLAR.

Application filed March 4, 1927. Serial No. 172,918.

The present invention relates to a horse collar and has for its principal object to provide a pneumatic collar of this nature having a novel structure whereby the bladders may be easily and readily inserted in the collar casing and the openings through which they pass may be secured firmly together.

Another very important object of the invention lies in the provision of a horse-collar of this nature which is exceedingly simple in its construction, inexpensive to manufacture, thoroughly efficient and reliable in use, comfortable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is an elevation of the horse-collar embodying the features of my invention,

Figure 2 is an enlarged detail section taken substantially on the line 2—2 of Figure 1,

Figure 3 is a perspective view of one of the clips,

Figure 4 is a plan view of one of the straps.

Referring to the drawing in detail, it will be seen that the numeral 5 denotes the casing of the collar which is substantially U-shaped in formation and has its sides hollow for receiving inflatable bladders 6 through open ends 7. The valves 8 project through openings in the casing 5 so that a pump may be engaged therewith for inflating the bladders. U-shaped clips C are disposed over the open ends of the casing 5 and include curved bights 9 and straight flat sides 10 having openings 11. A pair of T-shaped straps S have their transverse head portions 12 disposed in the open ends of the casing and formed with openings 13 to register with openings 11 so that bolts 14 may be inserted through openings 11 and 13 and corresponding openings in the ends of the casings to hold the parts assembled when

nuts 15 are screwed on said bolts. The straps S have their shank portions 16 extending towards each other and one has a buckle 17 secured thereto for receiving the other.

It is thought that the construction, utility, and advantages of this horse collar will be apparent to those skilled in this art without a more detailed description. The present embodiment of the invention has been disclosed in detail by way of example since in actual practice it attains the features of advantage enumerated as desirable in the statement of the invention and the above description. It will be apparent that changes in the details of construction, in the materials, and in the sizes may be resorted to without departing from the spirit or scope of the invention as hereinafter claimed or sacrificing any of its advantages.

Having thus described my invention, what I claim as new is:—

1. A horse-collar of the class described, including a casing substantially U-shaped in formation to fit about a horse's neck and having its sides hollow and its ends open, bladders fitted in the sides and inserted through the open ends, U-shaped clips disposed over the open ends, and bolts extending through the sides of the clips and the open end of the casing for holding said open end closed.

2. A horse-collar of the class described, including a casing substantially U-shaped in formation to fit about a horse's neck and having its sides hollow and its ends open, bladders fitted in the sides and inserted through the open ends, U-shaped clips disposed over the open ends, and bolts extending through the sides of the clips and the open end of the casing for holding said open end closed, T-shaped straps having their head portions disposed in the open ends between the sides of the U-shaped clips and pierced by said bolts and their shanks extending towards each other, one of said shanks having a buckle to receive the other of said shanks.

In testimony whereof I affix my signature.

WILLIAM S. ROGERS.
